NEW YORK

ADVERTISING DEVICE

Application filed December 1, 1927. Serial No. 236,993.

This invention relates to an advertising device, and particularly to an advertising device in the form of a scales, being in the nature of an improvement upon the structure shown and described in our pending application Serial No. 199,176.

The object of the present invention is to improve the form and operation of the advertising feature of the scales.

10 A further object is to provide means for inducing a user to remain in position observing the advertising items.

Other objects and aims of the invention, more or less specific than those referred to above, will be in part obvious and in part pointed out in the course of the following description of the elements, combinations, arrangements of parts and applications of principles constituting the invention; and the 20 scope of protection contemplated will be indicated in the appended claims.

In the accompanying drawing which presents a front elevational view, partly broken away, of a scales constructed in accordance with this invention, the reference character L indicates a base upon which is a depressible platform G. Rising from the base L is a column or standard 1 at the upper end of which is a head H having a window as 2 therein which is at, or approximately at, the eye level of a person standing upon the platform G.

Within the head H is arranged any suitable type of mechanism for showing the weight of the person standing upon the platform, such mechanism being indicated generally by the reference character 3 and including a graduated or other member 4 which is movable with respect to the window 2, said mechanism being connected with the platform G by means of a rod 5 extending downwardly therefrom through the standard 1, the arrangement being of the usual well known class in which when a person stands upon the platform G the graduated or like member 4 will present to the window 2, for observation by the person standing upon the platform, a figure corresponding to the weight of the person.

50 In the present improved structure there is

also arranged within the head a disc or wheel-like member 6 having an annular forwardly facing surface portion 7 upon which there is carried a series of advertising or like items as 8—8 end to end extending entirely around 55 said annular surface.

The window 2 provided in the head H may be sufficiently large to allow a view therethrough of the items 8—8, or if preferred a separate window as 9 may be provided 60 through the front wall of the head for this purpose.

The wheel of disc 6 is pivotally mounted as at 10 centrally of the head H and is adapted to be slowly rotated by means of an electric 65 motor device as 11. The motor may be connected with the wheel by any suitable gearing, there being shown for the purpose of illustration a worm pinion as 12 carried by the motor shaft and engaging worm teeth as 13 provided 70 upon the periphery of the wheel.

The motor 11 as heretofore is intended to operate for moving the advertising items successively past the window 9 throughout the time while a person is standing upon the 75 platform G. The rod 5 has carried thereby a contact finger 14 which is co-operative with a stationary contact finger 15 carried interiorly of the standard 1 in a position to be engaged by the finger 14 whenever the rod 80 moves downwardly for transmitting motion to the weight indicating member 4.

The circuit for the motor, as illustrated, includes a wire as 16 which leads from a suitable source to one side of the motor, a wire 85 as 17 which leads from the opposite side of the motor to the contact finger 14, and a wire 18 from the contact finger 15 to the opposite side of the source.

Whenever a person imposes his weight upon the platform G to operate the weight indicating member 4 he will at the same time involuntarily close contact between the fingers 14 and 15 and thus energize the motor and start operation of the advertising mechanism, the operation of said mechanism continuing so long as the circuit is maintained closed at contacts 14 and 15, during all of which time the advertising items will pass 90 95 100

successively before his vision, through the window 9.

As an urge to induce persons to remain upon the scales platform a sufficiently long time to inspect at least a goodly portion of the advertising items carried by the wheel 6 it is suggested that means be provided for at times obscuring the weight figure, and to this end the drawing illustrates an example of such means in that it shows the wheel 6 to be provided with an inwardly extending flange part 19 disposed to overlie the graduated member 4 in position for closing the window 2 so that the weight indications upon the weight member 4 will not be visible through said window while the flange part is passing.

There may of course be either one or any number of flange parts 19, and they may be of a circular length according to the will of the manufacturer.

By an arrangement of this character when a person steps upon the scales platform the member 4 will of course rotate but it may or may not at that time be visible through the window 2 according to the position of the part 19. The part 19 however, if not already obscuring the weight indication, will soon do so, and the user will doubtless remain upon the platform until his weight again appears, during all of which time the advertising items will be passing before him.

As many changes could be made in this construction without departing from the scope of the invention, as defined in the following claims, it is intended that all matter contained in the above description, or shown in the accompanying drawings, shall be interpreted as illustrative only and not in a limiting sense.

Having thus described our invention, what we claim as new and desire to secure by Letters Patent is:

1. An advertising device comprising a scales platform, a weight indicating member connected therewith, a movable advertising element arranged to be visible adjacent the weight indicating member said advertising element comprising a rotatably mounted wheel upon an annular portion of which items are carried, and means automatically operable by the imposition of weight upon the scales platform to thereby rotate the wheel continuously in the presence of said weight.

2. An advertising device comprising a scales platform, a weight indicating member connected therewith, a movable advertising element, a casing for said weight indicating member and said advertising element said casing having a window-opening therethrough, said advertising element consisting of a rotatably mounted wheel upon an annular portion of which items are arranged to be visible successively through the window whenever the wheel rotates, said wheel having worm teeth thereon, a worm pinion en-

gaging said worm teeth, a motor for driving said pinion, and a circuit for said motor including a switch device arranged to be moved to on position by the weight of a person standing upon said scales platform.

3. An advertising device comprising a scales platform, a weight indicating member connected therewith, a movable advertising element arranged to be visible adjacent the weight indicating member, means to move said advertising element, and means connected rigidly with the advertising element so as to move therewith at all times during movement of the advertising element effective for periodically obscuring the weight indicating member.

4. An advertising device comprising a scales platform, a weight indicating member connected therewith, a movable advertising element arranged to be visible adjacent the weight indicating member, means connected to be operated by movement of said platform for causing movement of said advertising element, and means also effective as a result of movement of the platform to obscure the weight indicating member.

5. An advertising device comprising a scales platform, means connected therewith providing two features visible for inspection by a person standing upon said platform, and means whereby down movement of the platform by the weight of a person standing thereon will cause one of said features to move and the other to become obscured.

6. An advertising device comprising a scales platform, a weight indicating member connected therewith, a movable advertising element arranged to be visible adjacent the weight indicating member, said advertising element comprising a rotatably mounted disc, means operable by the imposition of weight upon the scales platform to rotate said disc continuously in the presence of said weight, and a plate fixed to the disc to rotate therewith adapted thereby to overlie and conceal the weight indicating member periodically at least once with each complete rotation of the disc.

7. An advertising device comprising a scales platform, a weight indicating member connected therewith to be operated thereby, a movable advertising element arranged to be visible adjacent the weight indicating member, means operable by the imposition of weight upon the scales platform effective to move the advertising element continuously in the presence of said weight, and means whereby the weight indicating member will be alternately obscured and revealed a plurality of times continuously in the presence of weight upon the platform.

In testimony whereof we affix our signatures.

JAMES E. O'BRIEN.
